(57) **CLAIM**

The ornamental design for an ultrasound case, as shown and described.

DESCRIPTION

FIG. 1 is a perspective view of an ultrasound case according to the present invention;

FIG. 2 is a rear perspective view thereof;

FIG. 3 is a front elevation view thereof;

FIG. 4 is a rear elevation view, rotated 180°, thereof;

FIG. 5 is a right side elevation view, rotated 90°, thereof;

FIG. 6 is a top view thereof;

FIG. 7 is a bottom view thereof; and,

FIG. 8 is a left side elevation view, rotated 90°, thereof.

The broken lines in the drawing are for illustrative purposes only and form no part of the claimed design.
